UNITED STATES PATENT OFFICE.

MATTHEW R. HULL, OF CONNERSVILLE, INDIANA, ASSIGNOR TO REX MANUFACTURING COMPANY, OF CONNERSVILLE, INDIANA, A CORPORATION OF INDIANA.

JOINT-MASKING MEANS FOR DEMOUNTABLE AUTOMOBILE TOPS.

Application filed January 2, 1920. Serial No. 349,015.

To all whom it may concern:

Be it known that I, MATTHEW R. HULL, a citizen of the United States, residing at Connersville, in the county of Fayette and State of Indiana, have invented certain new and useful Improvements in Joint-Masking Means for Demountable Automobile Tops, of which the following is a specification.

This invention relates to certain means for concealing the point formed between the meeting edges of an open vehicle and body and its closed top, being a continuation in part of my copending application Serial No. 243,302; and the principal object of the present invention is to provide means for internally and externally masking the joint formed at the meeting edges of the vehicle body and its independently formed closed top, thereby concealing the divisional character of the unitary appearing structure.

The above mentioned object, and such others as may appear from a perusal of the following description, I attain by means of the construction and arrangement of parts as illustrated in the accompanying drawing, forming a part hereof, in which—

Figure 1 is a fragmentary detail perspective view of the rear portion of a motor car tonneau and closed top, showing my improved joint masking means in operative position. Fig. 2 is a fragmentary detail perspective view, showing more clearly the means for masking the joint inside the vehicle. Fig. 3 is a side elevation of the construction shown in Fig. 2. Fig. 4 is a fragmentary detail sectional view, on the line 4—4 in Fig. 3. Fig. 5 is a fragmentary detail cross sectional view, on a considerably enlarged scale, showing the arrangement of the parts adjacent the meeting edges of the body and the top. Fig. 6 is a cross sectional view of the parts near the meeting edges of the body and top, showing a modified form of the joint masking means.

Referring to the drawings, 10 represents the rear portion of an open automobile body, 11 a demountable top, and 12 one of the upper door extensions or panels extending up from the door 13 of the permanent body 10 and closing the door-opening in top 11. The lower edges of top 11 and panels 12 are arranged upon the upper edge of and in vertical alinement with the inner and outer faces of the permanent body 10, in the manner most clearly shown in Fig. 5. Top 11

and panels 12 are preferably secured to body 10 by means of metal strips 15 which are of a width to extend a sufficient distance on both sides of the joint formed by the meeting edges of the body and top to admit the attachment of the body by means of the screws 16 and of the top and panels by means of the screws 18. Metal strips 15 are provided with numerous elongated slots 20 through which the attaching screws 16 pass, these slots permitting slight adjustments in overcoming minor structural variations when fitting the tops and panels into operative position on body 10. As will readily be observed, the above construction not only provides a firm anchorage for the top and side panels, but provides an easy means whereby the parts which are superimposed upon body 10 may easily be set up or taken down. As it may be desirable to remove top 11 and side panels 12 in the spring and replace them in the fall of the year, strips 15 and securing screws 16 of necessity must be readily accessible. It is desirable, when the demountable top and panels are in operative position, to have the joint formed between the meeting edges of the top, side panels and body, and also strips 15 and strip-attaching screws hidden from view so as not to mar the interior appearance of the body and top, and it is one of the purposes of the present invention to completely conceal the joint, metal strips and attaching screws, but leaving said strips and attaching screws readily accessible when necessary. The above object is accomplished by running the interior trimming or upholstery material 25 in body 10 from the floor line 26 upwardly and to the upper edge of said body. The upholstery material 28 extends downwardly from the ceiling of top 11 and extends sufficiently below the lower edges of side panels 12 to provide flaps 30 of sufficient length to completely cover and conceal strips 15. The lower edges of flaps 30 are generally stitched so as to provide a finish in the nature of a bead and, as indicated in Fig. 1, imparts the idea that instead of a break occurring in the lining a horizontal band or frieze extends along the inner sidewalls of the body and top, thereby destroying the extreme plainness of a normally large exposed surface area of upholstery. In order to prevent the free edges of flaps 30 from curling out and keep them in contact with

the surface of the adjacent body wall, I provide a number of spring-fastening devices 35, similar to glove fasteners, which are secured to flaps 30, and these fasteners 35 are adapted to take over the heads of screws 36 which are mounted in and project a slight distance away from the surface of strips 15.

By means of the above construction, it will be seen that when flaps 30 are fastened down they completely hide strips 15 and attaching screws so that no part of the rough structural frame-work is observable, and at the same time flaps 30 may easily be loosened so as to render the attaching screws in strips 15 readily accessible when it is desired to place the top into or out of operative position.

The open joint formed between the meeting edges of the body 10, top 11 and panels 12 is concealed on the external surface of the body and top by means of a molding 40 which is secured to or integral with and depends below the lower marginal edges of top 11 and panels 12 a sufficient distance to conceal the joint (as shown in Figs. 1 and 5), the molding 40 being removed with the top and panels so as to leave the upper edge of body 10 free of obstructions when top 10 is not in use.

30 Fig. 6 shows a modified form of the joint masking molding 40^a having rather small dimensional thickness as compared to the width, similar to a band, as distinguished from the half-round molding 40 shown in

35 Figs. 1 to 5, inclusive.

Having thus fully described my said invention, what I desire to secure by Letters Patent is—

1. The combination with the lower open section of an automobile body, of a detachable top and upper side section having a bottom rim conforming to the top rim of said lower section, said top section having an external depending flange in the form of 45 an ornamental bead masking the joint between the upper and lower sections externally and a lining for said upper section having a depending apron masking the joint between the upper and lower sections inter-

50 nally.

2. An automobile body comprising a per-

manent lower section, a demountable upper section having a lower rim conforming to the upper rim of the lower section and having side walls equal in thickness to those of the lower section, an ornamental outer bead carried by the demountable section and concealing the joint between the sections externally, and a lining for the demountable section extending downward from the ceiling and concealing the joint between the sections internally, substantially as set forth.

3. The combination with the lower open section of an automobile body, of a detachable top section having a frame as thick as and conforming to the rim of the lower section, the top section having a lining and an external molding both of which extend below the frame to form a channel for the rim of the lower section, and means arranged in said channel to hold said sections connected.

4. The combination with the lower open section of an automobile body, of a detachable top section having a frame as thick as and conforming to the rim of the lower section, said sections being arranged in edge-to-edge relation, and external means and internal means constructed and arranged to conceal the sectional character of the combination and to present the visual effect of 80 a unitary closed body.

5. The combination with the lower open section of an automobile body, of a detachable top section having a bottom rim conforming to the top rim of said lower section, said top section having an external joint masking molding and a lining of flexible sheet material both depending below said bottom rim to form a channel for inclosing said top rim of the lower section, the depending marginal portion of said lining being arranged to cover sufficient of the internal surface of the upstanding walls of said lower section to conceal the joint between the sections internally, substantially 95 as set forth.

In witness whereof, I have hereunto set my hand and seal at Connersville, Indiana, this 27th day of December, A. D. one thousand nine hundred and nineteen.

MATTHEW R. HULL. [L.S.]
